Patented July 13, 1976

240,478

PEDESTAL ARM CHAIR

William Sklaroff, Narberth, Pa., assignor to John Stuart
International Inc., New York, N.Y.

Filed Feb. 26, 1975, Ser. No. 553,304

Term of patent 14 years

Int. Cl. D6—01

U.S. Cl. D6—31

FIG. 1 is a perspective view of a pedestal arm chair taken from the front left side of same;

FIG. 2 is a plan view of the chair shown in FIG. 1;

FIG. 3 is a side elevational view of the chair shown in FIG. 1 taken from the right side;

FIG. 4 is a rear elevational view of the chair shown in FIG. 1;

FIG. 5 is a bottom view of the chair shown in FIG. 1; and

FIG. 6 is a side elevational view of the chair shown in FIG. 1, taken from the right side, with a modified exterior back.

I claim:

The ornamental design for a pedestal arm chair, as shown and described.
